Primary Examiner — Manpreet S Matharu*Assistant Examiner* — Yolanda Robinson(74) *Attorney, Agent, or Firm* — Paratus Law Group,
PLLC(57) **CLAIM**The ornamental design for a container for endoscope drape,
as shown and described.**DESCRIPTION**

FIG. 1 is a front view of a container for endoscope drape showing our new design;

FIG. 2 is a back view thereof;

FIG. 3 is a right side view thereof;

FIG. 4 is a left side view thereof;

FIG. 5 is a plain view thereof;

FIG. 6 is a bottom view thereof;

FIG. 7 is an A-A' Sectional view thereof;

FIG. 8 is a B-B' partial enlarged view thereof;

FIG. 9 is a partial A-A' section end view of left and right portions thereof with a center portion removed;

FIG. 10 is a C-C' partial enlarged view thereof;

FIG. 11 is a front perspective view thereof;

FIG. 12 is a back perspective view thereof; and,

FIG. 13 is a B-B sectional view thereof.

The broken lines are used for environmental purposes only and form no part of the claimed design.

1 Claim, 13 Drawing Sheets(56)
